UNITED STATES PATENT OFFICE.

FREDERICK L. McGAHAN, OF LOS ANGELES, CALIFORNIA.

TURBINE-LOCOMOTIVE.

1,324,427.

Specification of Letters Patent.

Patented Dec. 9, 1919.

Continuation in part of application Serial No. 210,146, filed January 3, 1918. This application filed October 14, 1918. Serial No. 258,127.

To all whom it may concern:

Be it known that I, FREDERICK L. McGAHAN, a citizen of the United States, residing at the city of Los Angeles, in the 5 county of Los Angeles and State of California, have invented certain new and useful Improvements in Turbine-Locomotives, of which the following is a specification.

This is a continuation in part of an application filed by me January 3, 1918, serially numbered 210,146, that issued as Patent 1,292,399, dated January 21, 1919.

This invention relates to a steam turbine of the radial impulse type, and is illustrated 15 as applied to the auxiliary driving of a locomotive engine, with the construction suitable for such application by means of which more power is derived for the said purpose and applied thereto, not only because of the 20 use of the said turbine as part of the driving mechanism but, also, because of the application of the power through a plurality of turbines (where desired) and a plurality of wheel groups, which results in greater power 25 being exerted upon the train by the locomotive. All this is accomplished with an economy of steam, not only because steam is used more than once for power and afterward can be used for heating the train, but, also, 30 because the herein-described mechanism enables the derivation of power from steam of lower pressure than is now useful for that purpose, whereby, as may be said, all the power of the steam (instead of, as now, only 35 part of its power) is utilized. Moreover, this mechanism eliminates wasteful and objectionable gas, smoke, sparks, and cinders by drawing the same out of the firebox and returning the solid particles thereto for further 40 combustion. Other economies, advantages, and improvements will hereinafter appear.

In the accompanying drawings forming 45 part of this specification and in which like numbers of reference denote like parts wherever they occur,

Figure 1 is a side elevation of a quadruple driven locomotive illustrating the application 50 of the steam turbine;

Fig. 2 is a vertical section of the turbine taken on the line 2—2 in Fig. 3.

Fig. 3 is a section taken on the line 3—3, Fig. 2;

Fig. 4 is an enlarged plan view of the gov- 55 ernor;

Fig. 5 is an elevation of the governor taken on the line 5—5, Fig. 4;

Fig. 6 is an enlarged fragmental sectional view around the rotor valves taken on the line 6—6, Fig. 7;

Fig. 7 is an enlarged fragmental sectional view taken on the line 7—7, Fig. 6;

Fig. 8 is a view taken on the line 8—8, Fig. 6;

Fig. 9 is a similar section like Fig. 2, 65 illustrating a modified form of governor and rotor valves, taken on the line 9—9, Figs. 10, 11, and 12;

Fig. 10 is a plan section, taken on the line 10—10, Fig. 9;

Fig. 11 is a plan section, taken on the line 11—11, Fig. 9;

Fig. 12 is a plan section, taken on the line 12—12, Fig. 9;

Fig. 13 is an enlarged fragmental sec- 75 tional view around the modified form of rotor valves, taken on the line 13—13, Fig. 15;

Fig. 14 is a view taken on the line 14—14, Fig. 15;

Fig. 15 is an enlarged fragmental sec- 80 tional view, taken on the line 15—15, Fig. 13;

Fig. 16 is a diagram, illustrating a devel- 85 opment of the circular cam, for tripping the valve levers;

Fig. 17 is a similar diagram;

Fig. 18 is also a similar diagram;

Fig. 19 is an enlarged view of the gov- 90 ernor gear segments;

Fig. 20 is a fragmental sectional perspec- 95 tive of the fan;

Fig. 21 is a section on the line 21—21, Fig. 1; and

Fig. 22 is a section on the line 22—22, 95 Fig. 1.

The locomotive 1 is provided with the customary driving-wheels 2 and forward truck-wheels 3. Driving-wheels 2 are driven from cylinder 5 in the usual manner. The tender 100 truck-wheels are in two sets, one set being driven by the other. Thus it will be seen that a quadruple-drive is applied to the locomotive, the same steam being used for all, and may be afterward used for heating the 105 train. By the system herein described a greater proportion of the energy of the steam is utilized for driving purposes than is attained in prior locomotives, so much so that this apparatus derives driving force 110

from the steam until the steam is reduced to only four or five pounds' pressure, after which it may be used for heating, as above stated.

5 A turbine 6, which rotates the shaft 7, drives the truck-wheels 3; and the turbine 8, which rotates the shaft 9, drives the truck-wheels 4. Both these turbines are of the same construction, with the exception that 10 turbine 8 has no fan or smoke pipe, as hereinafter described. The locomotive 1 is adapted to travel in either direction, which is particularly true in view of the location of one of the said turbines at each end 15 thereof.

The smoke stack 10 will normally not be used, because of the draft of smoke and cinders as hereinafter described and the return of the cinders to the fire-box 11 by an 20 automatic screw-stoker (not shown) and the mixture of the smoke with the steam in the turbine 6.

The initial superheated steam is conveyed from the boiler 12 through the manifold 25 or divider 13 to and through the pipes 14 and 15 to both sides of the locomotive and admitted to cylinder 5 and after said steam has been used in cylinder 5 to drive the piston rod 16 and thus the main driving-wheels. 30 2 in the customary manner, the steam exhausts from said cylinder 5 into the passages 17 and 18, leading to pipes 19. Said passages are conveniently connected to the intake pipes 19 of the turbine 6, therefore 35 the pony truck turbine 6 uses an intermediate pressure of steam, which is the exhaust from cylinder 5. This steam passes through pipe 19 and thence into the chamber 20 surrounding the revoluble rotor 21 having helical grooves in its surface adapted to receive frictional and impelling contact from the incoming steam, thereby deriving its rotary motion and driving shaft 7 which is connected to trucks 3.

40 45 The turbine 6 can be cut in or out by use of valves 22 and 23, which are operated from the cabs through reach-rods 24 by any convenient method.

Having thus energized the turbine 6, the 50 steam passes through exhaust pipes 25 to energize turbine 8, the said pipes 25 being located on each side of the locomotive 1. The rotary motion of rotor 21 rotates shaft 9, which thereby drives truck-wheels 4, the 55 righthand set of which in Fig. 1 is driven from the lefthand set in the said figures, by any convenient method. Driving of the said wheels may be accomplished in any other suitable manner, as, for instance, by 60 beveled gears, a universal shaft, or the like. It should be understood that the action of turbine 8 on shaft 9 and trucks 4 is the same as that of turbine 6 on shaft 7 and trucks 3, with the exception that truck-wheels 4

are a double set as compared with truck- 65 wheels 3.

Each rotor 21 is of substantially the same construction and mounted and connected in substantially the same manner. Upon the support 26 above the trucks is fastened a 70 ball-race 27, which bears the bottom of the rotor 28.

The fan 29 has a hub 90 fixed to the shaft 7 having a plurality of cups 91 adapted to connect to the flange 34. 75

The cups 91 open in the direction toward which they rotate, tending to force the intake. The shape within each cup diverts the air from its direction when admitted to a direction approximately at an angle of 80 90 degrees thereto.

Fan 29 draws hot air, smoke and cinders through pipes 30 from the top of the fire-box 11, into the hollow chamber 50 of the rotor 21, and thereby the steam that enters 85 chamber 20 through pipes 19 is reheated or superheated, because the hot flames and gases heat the metal of the rotor 21 thereby reheating and drying the exhaust steam from the cylinders 5, after the said steam enters 90 the chamber 20. A ball race 27 coöperates with a groove in the bottom 28 of rotor 21 and a groove in support 26 and 31, also, a ball race 32, coöperates with a groove 33 in the flange 34 of the fan 29, and a groove 95 35 in the rotor housing 36, thereby allowing the rotor 21 to rotate freely as impelled by the action of the steam admitted through pipes 19, upon the helical grooves 37, and, thereby rotating shaft 7, to which is fixed 100 the said rotor 21. After the steam has passed through the chamber 20 of the helical grooves 37, it then passes into the chamber 38 of the support 26 and thence through pipe 25 to turbine 8. 105

The steam passes through the pipe 25 along each side of the locomotive 1 to a vertical portion of the pipe 25 at 39 and through this portion of the pipe to the continuation of pipe 25 numbered as shown in 110 Fig. 1 at 40.

The object of this vertical pipe 39 is to provide means of separation of the steam from the water, *i. e.*, to take the humidity out of the steam which is actuated by gravity, the water dropping to the bottom of the T 41 and flowing to a filtering mechanism 42.

This turbine 8 may be run independent of 115 low pressure steam, as it has two connections. The one connection to the pipe 40 which is the low pressure steam pipe and the pipe 43 which is connected directly to the superheating coils 44. Thus when the engine is standing still and turbine 8 is desired to run for the making of electricity, pumping air, or some other reason, by turning off steam from pipe 40 and cutting in 120 125

high pressure steam from pipe 43 this object can be accomplished. After the steam has passed through the turbine 8 in its specific operation it enters a radiator or 5 condenser 47 through which it passes and emerges as water. The water then passes through pipe 48 in a filter 42, where it is freed from the last traces of boiler scale, residue, and grit, then flowing through pipe 10 45 to the water-tank 46 of the tender and thence is pumped back into the boiler as distilled water, by any common pump as shown at 49.

Fuel, preferably pulverized, is normally 15 fed into the fire-box 11, through nozzles 11^b, by any mechanical stoker (not shown in the drawings). The smoke, soot, cinders, and the like are drawn into the turbine 6 through the pipe 30, from the fire-box 11, by the 20 suction caused by the fan 29, and are drawn through the said fan into the chamber 50 of the rotor 21.

After the smoke has been drawn into the chamber 50 by action of fan 29 (which also 25 draws the cinders and sparks from the fire-box, flue, or smoke-pipe 30) steam is admitted into the said chamber 50 through as many valve orifices 51 as will properly condense said smoke, sparks, cinders, and 30 soot by its being rapidly revolved and churned therein, so that, after its exit from turbine 6, same may be discharged through a stoker back into the fire-box 11.

Piston compression blades 72 are helical 35 in form and may be of any desired pitch. Said blades 72 are held against the highly ground surface of the rotor housing 36 at 73 by means of flat zigzag springs 74, said springs 74 being tempered to hold blades 72 40 in a fixed position against the said surface 73.

The opening of valves 52 is accomplished 45 through a flyball governor, having balls 53 on the end of a bell crank lever 54, pivot-ally bolted to the flange 55 by means of a bolt 56, and having on the short arm of the bell-crank 54, a cam 57 which by means of a groove 58 and a roll 59 raises the sleeve 60, to which is fixed the cam wheel hub 61 of 50 the cam 62.

When the governor balls 53 expand by centrifugal force, tension is caused on the springs 63, and as the bell-crank 54 begins to rotate around the pivot bolt 56, the cam 55 57 with the groove 58 tends to rotate about this said pivot 56, and, the lever 54 being secured to the flange 55, the sleeve 60 tends to ride upward over the shaft 7 of the turbine 6.

60 The sleeve 60 has fixed thereto a cam 62 which moves therewith. The cam wheel comprises a hub 61, fixed to the sleeve 60 with arms 64 adapted to connect to the cam 62.

65 Holes 65, reamed in the rotor 21, receive

the bushing 66, in which is pivoted the valve bell-crank lever 67, by means of a pivot pin 68. The bell-crank lever 67 has a jaw end 69 adapted to receive the cam 62, and a valve plate 70 adapted to open and 70 close the orifice 51.

The cam 62 may have one or more offsets 71, as shown in Figs. 16, 17, and 18, and these offsets 71 can be timed for rests and trippings of the valve lever 67, as the 75 conditions may warrant.

The offset position of a valve is shown in dotted lines of Fig. 6.

The path of the steam is indicated by arrows in Figs. 2 and 9, and, as shown, the 80 steam passes through an open valve, while the other two valves are closed; illustrating that one valve may be opened while the other remains closed.

The steam, in its predetermined path, and 85 the smoke pass through the openings 75 between the ribs 76. Ribs 76 are adapted to the hub 77, and the bottom of the rotor 28, and the smoke and gases pass into the chamber 78 of the support 26, and thence into 90 the pipe 79, after which the mixture of smoke, steam, sparks, and soot is carried by steam pressure and fan action to the stoker, to be reburned in the fire-box 11.

On the rotor housing 36, is secured by 95 bolts 81, the cap plate 80, having a center hub 82, in which the shaft 7 rotates; and, at the bottom or smaller diameter of the rotor housing 26, is a flange 83, which is secured to the support 26 by means of bolts 84. 100

On the end of the shaft 7, there is fixed a worm 85 and a worm wheel 86, but it is evident that bevel gears, spiral gears, spur gears, and the like, could be used as well as those shown, with a shaft 87 fixed to the 105 driven member 86, which shaft may be the axle of the wheels 3.

In Fig. 9, a modified form of governor is illustrated having balls 53, bell-crank lever 54, flange 55, bolt pivots 56, gear segment 110 57^a, teeth 58^a, gear segments 59^a, sleeve 60, and springs 63.

When the centrifugal force, as applied to the balls, becomes so great as to spread the balls, shown in Fig. 11, in dotted lines, then, 115 gear segment 57^a moves gear segment 59^a turning sleeve 60, over the shaft 7 of turbine 6. Shaft 7 has a helical groove 88, in which the roller or lug 89 of the sleeve 60 plays, riding upward and carrying sleeve 60 120 with it as hereinbefore specified.

The action of the cam 62 and valve levers 67 are precisely the same as hereinbefore described, with the exception that valve plate 70^a may be of a rectangular shape, 125 covering the orifice 51 and overlapping the bushing 66, as is clearly shown.

One object of the turbine 6 and the vacuum fan 29 is to create a draft from and through the fire-box, taking by suction any 130

- back pressure from the cylinders 5 and the piston blades 72 of turbine 6, giving the same condition that is caused by the jet condenser in the well-known stationary engine.
- 5 A further object is to draw all smoke, cinders, and sparks through the vacuum fan 29 and to keep a more even draft, just the necessary draft to create and regulate a perfect blaze, in the fire-box and through the flues 10 of the locomotive.

It will be understood by locomotive drivers and engineers that after the superheated steam has passed through the ordinary high pressure cylinders, the steam will 15 have lost only a comparatively small percentage of its mean effective pressure, so that when the steam enters the grooves on the turbine (instead of exhausting into the open air to create a draft), which grooves 20 are helical for two-thirds of the circumference of the said turbine, the said steam exerts sufficient force to insure powerful rotation of the said turbine.

It will be understood that the interior of 25 the shell of the turbines inclosing the rotor 21 is ground or otherwise formed perfectly smooth, so that the piston blades 72 will form a tight fit and wear evenly, while serving perfectly to control the steam. Any 30 such contacting parts of the apparatus will be made of a suitable bronze alloy hardened with vanadium, so as to give a good wearing surface with the steel surface of the said shell.

35 The tender turbine 8 equipped with a fan 29 may be so run while the locomotive is standing still as to blow powdered fuel into the fire-box, instead of the said powdered fuel being drawn thereinto, as hereinbefore 40 described.

There is a distinct advantage in power in applying driving power to wheels located along an increased trackage. While the ordinary locomotive drives only by its driving 45 wheels, this locomotive does not discard that ordinary form of driving, but adds to it driving the pony trucks at the extreme front of the locomotive and the two sets of tender trucks at the rear end of the combined and 50 connected tender and locomotive. This separate driving increases the pulling power of the engine. A great advantage is acquired, also, by the superheating of the steam in the interior of the turbine rotor 21 (chamber 55 50) in the locomotive turbine 6, due to the draft thereinto by the adjacent fans 29 of the hot air direct from the fire-box through pipes 30.

These features may all be adapted to any 60 locomotive now in existence and one or more of the turbines may be applied by utilizing an additional set of driving trucks on either end of the locomotive, and thus using only the exhaust steam to drive the same.

65 By this construction, the heavy and te-

dious work of the fireman will be abolished, leaving him free to render other assistance to the engineer, such as watching the track and preventing accidents from misplaced switches or obstructions or stock upon the 70 roadway.

The turbine 8 may or may not have a fan 29.

While the turbines are herein illustrated and described as utilized in connection with 75 a locomotive engine, they can be used in other situations, in which event water or steam may be used as the motive power.

Having thus described this invention, it is obvious that many minor changes in the 80 form, arrangement and order of parts and their materials and mode of construction may be made without departing from the spirit of this invention or the scope of the following claims. 85

I claim:

1. A locomotive turbine having a central shaft, means in connection with the said shaft for driving the locomotive wheels, a truncated cone fixed to the said shaft, the 90 said cone having grooves on its periphery, and means for the inlet and exhaust of steam.

2. A locomotive turbine having a central shaft, means in connection with the said 95 shaft for driving the locomotive wheels; a truncated cone fixed to the said shaft, the said cone having grooves on its periphery and means for the inlet and exhaust of steam, and a governor for regulating the admission and exhaust of steam. 100

3. In a locomotive, the combination of a turbine having grooves upon its surface, steam pipes adapted to admit steam tangentially into the said grooves, a shaft 105 adapted to be rotated by the said turbine, a fan-carrying member supported above the said turbine, the said fan-carrying member surrounding and rotatable by the said shaft, anti-friction bearings for the said member, 110 fans borne thereby connecting with the interior of the said turbine, and pipes leading from the fire-box to the said fans.

4. The combination of a turbine, steam inlet and exhaust pipes, a furnace, and a fan 115 adapted to serve as a forced draft for the said furnace.

5. The combination of a turbine, steam inlet and exhaust pipes, a furnace, and a fan adapted to serve as a forced draft for the 120 said furnace, the said fan being rotated by the rotor of the said turbine.

6. The combination of a turbine, steam inlet and exhaust pipes, a furnace, and a fan adapted to serve as a forced draft for the 125 said furnace, the said fan being rotated by the rotor of the said turbine, and the said fan comprising a plurality of cups opening in the direction toward which they move.

7. The combination of a turbine, steam in- 130

let and exhaust pipes, a furnace, and a fan adapted to serve as a forced draft for the said furnace, the said fan being rotated by the rotor of the said turbine, and the said fan comprising a plurality of cups opening in the direction toward which they move, and so shaped within as to be adapted to

force the air taken into them in a direction substantially at a right angle to the direction of first intake.

10

In testimony whereof I hereunto affix my signature.

FREDERICK L. McGAHAN.
